US00D664624S

(12) United States Design Patent
Orsulak et al.

(10) Patent No.: US D664,624 S
(45) Date of Patent:  Jul. 31, 2012

(54) EXERCISE APPARATUS

(75) Inventors: James Michael Orsulak, Knoxville, TN (US); Montgomery Scott Kiburn, Knoxville, TN (US); Bobby Daryl Shute, Knoxville, TN (US); Daniel L. Webb, Newburgh, IN (US)

(73) Assignee: Power Systems Inc., Knoxville, TN (US)

() Term: 14 Years

(21) Appl. No.: 29/399,977

(22) Filed: Aug. 22, 2011

(51) LOC (9) Cl. 21-03

(52) U.S. Cl. D21/826

(58) Field of Classification Search D21/811, D21/814, 823-827, 662, 670, 686; 482/35-36; 472/118

See application file for complete search history.
